UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

CARBURETOR.

Application filed July 11, 1921. Serial No. 483,994.

This invention relates to carburetors and particularly to carburetors for hydrocarbon motors.

Carburetors have been built heretofore in which there are valves or other moving parts connected to the fuel nozzle for the purpose of regulating the size or delivery action of the fuel outlet, which valves or parts have been connected to air valves or the motor throttle or other controlling devices in an attempt to furnish a correct mixture to the motor at all speeds and loads. Some of these are more or less successful for a time, but because of the difficulty encountered in handling such a small quantity of liquid fuel relative to the air required for the mixture the needle valves present a very difficult manufacturing problem and their operation is usually somewhat erratic or soon becomes so with use.

It is therefore one of the objects of the present invention to provide a carburetor in which the fuel orifices or outlets are fixed and so formed that they may be reamed to an exact size and are unencumbered by valves or other moving parts, and in which a proper mixture of liquid fuel and air may be delivered to the motor throughout its range of operation.

Another object of the invention is to provide a carburetor with a nozzle and mixture tube combination such that the liquid fuel will be supplied thru a small orifice at relatively low suction and thru an additional orifice after the suction has increased due to a greater demand of the motor for the mixture, to thereby effect an economy in the use of fuel.

Other objects of the invention will appear from the following description taken in connection with the drawings which form a part of this specification, and in which:

Figure 1 is a vertical section thru a motor intake pipe and a carburetor embodying the invention; and

Figure 2 shows a slightly modified form of nozzle.

Referring to the drawings, 10 represents a cylinder block of a hydrocarbon motor and 11 is the intake pipe thereof. The motor throttle is shown at 12 and the intake pipe is bent downwardly and is connected to a carburetor 13 by the flanges 14 and bolts 15.

The carburetor comprises a mixing chamber 16, a float chamber 17 of usual construction, a main air intake 18, and an auxiliary air intake 19. The main air intake may be controlled by a butterfly valve 20 for choking the carburetor when starting and the auxiliary air intake 19 is preferably controlled by an air valve 21 having a spring or springs 22.

A float 23 in the float chamber operates a valve 24 which controls the inlet port 25 in the usual way to maintain the liquid fuel in the float chamber at the required level. A supply pipe 26 communicates with the port 25 to supply the fuel.

Mounted in the lower part of the mixing chamber 16 is a mixture tube 27 which is shown of venturi form and in communication at its lower end with the main air intake 18. Thus the air entering the carburetor thru the main air intake passes upwardly thru the mixture tube 27 and the air from the auxiliary air intake 19 passes upwardly around the outside of the mixture tube 27 into the mixing chamber 16.

The carburetor is provided with a nozzle 28 which is suitably secured therein and the lower end of which communicates with the float chamber thru a passage 29. This nozzle is preferably formed of two tubes 30 and 31, as shown, and a plug 32 by which it is secured in place. The outer tube 30 is secured in the plug 32 and the inner tube 31 extends into the outer tube. The upper end 33 of the outer tube is separated from the exterior of the inner tube to form a well 34 and the upper end of this well is so located relative to the mixture tube 27 and the float chamber 17 that it is approximately at the neck of the Venturi tube and slightly above the level of the fuel in the float chamber. A restricted port or orifice 35 in the inner tube determines the amount of fuel that may be fed to the well 34.

This well 34, formed as shown, has several advantages; first, because of its free open upper end and its restricted inlet orifice 35 it will feed liquid fuel to the venturi at the correct ratio for idling and relatively low suction without danger of leakage when the motor stops, and second, when the motor is started the well will supply a rich mixture momentarily but without a continuation of it that is likely to choke the motor. If the

well were not provided the orifice 35 would of course have to be raised above the normal level to prevent leakage when stopped and then at low suction the fuel would not be drawn out of the orifice in the desired quantities.

For the higher suction when the maximum power of the motor is required the nozzle is provided with an extension outlet 36 which passes upwardly entirely thru the mixture tube 27 and into the mixing chamber 16 so that its end 37 discharges into the mixing chamber. Thruout the length of this extension the interior is considerably restricted so that it will act frictionally on the liquid passing thru it and thus retard it to some extent. Near its upper end, as at 38, its final restriction is located so that it may be reamed to an exact size, as is also the restricted orifice 35 before the tubes 30 and 31 are put together.

From the above description of the construction of the fuel nozzle it will be seen that the well 34 will be nearly full of fuel when the motor is idle and as soon as the motor is turned over, thus creating suction in the intake pipe 11, this liquid fuel will be drawn into the mixture tube 27 and the mixing chamber 16 with the incoming air and a rich mixture will be formed for starting the motor. As soon as the well 34 has been emptied the small port 35 determines the amount of gasoline fed to the mixture tube and this is sufficient for idling and for the lower running speeds or low suction. When a greater suction prevails however the liquid fuel will be drawn up farther in the nozzle and will discharge from the outlet 37 directly into the mixing chamber 16. This additional supply of liquid fuel will compensate for the additional air that is drawn in thru the intake 19 by reason of the larger suction and the mixture will be properly proportioned for the heavier duty required. It is retarded by friction as it passes thru the extension 36 sufficiently to prevent an over-rich mixture at very high suction. The nozzle is entirely free from valves or other moving parts and both of its orifices or outlets are at all times in the main air stream of the carburetor.

In Figure 2 a slightly different form of nozzle is shown. The plug 32 and outer tube 30 are exactly the same but the inner tube 55 41 has its large bore extending up to the orifice 45 and the small bore of its extension 46 is of minimum diameter all the way up from the orifice 45. This permits making the bore smaller above the orifice 45, and 60 therefore provides more surface friction for the fuel above that point, without at the same time restricting the capacity of the orifice 45. This will provide a leaner mixture at the higher speeds.

It will be understood that various forms

of the invention other than those described above may be used without departing from the spirit or scope of the invention.

Having described my invention, what I claim and desire to secure by Letters Pat- 70 ent is:

1. A carburetor comprising a float chamber, a mixture tube adjacent thereto, and a fuel nozzle connected to the float chamber and having a well opening into the mixture tube slightly above the liquid level and having a second opening somewhat above the top of the well and in the main air-stream. 75

2. In a carburetor, the combination with a Venturi mixture tube, of a fuel nozzle 80 therein having a well opening into said Venturi tube adjacent its neck and having a second opening above the well and in the main air-stream.

3. In a carburetor, the combination with a Venturi mixture tube, of a fuel nozzle extending into and thru the tube and having a well opening into the tube at its narrowest part and having a second opening above the top 85 of the tube and at all times in the main air-stream. 90

4. A carburetor comprising a float chamber, a mixture tube adjacent thereto, and a fuel nozzle connected to the float chamber and having a well with its only outlet means 95 opening into the mixture tube slightly above the liquid level and having a second opening somewhat above the top of the well and in the main air-stream.

5. A carburetor comprising a float chamber, a mixing chamber, a main air intake, a secondary air intake, a mixture tube communicating with the main air intake and extending into the mixing chamber, and a fuel nozzle having a well discharging into the mixture tube and having a discharge outlet 105 in the mixing chamber. 100

6. A carburetor comprising a mixture tube and a duplex fuel nozzle therein, said fuel nozzle being formed of an inner tube 110 and an outer tube, the inner tube extending somewhat above the upper end of the outer tube and the outer tube being cut away to form a well at its upper end around the inner tube, the inner passage of the nozzle communicating both with the upper end of the inner tube and with said well, and said well below its upper end communicating only with the inner passage of said nozzle. 115

7. A carburetor comprising a mixture tube, and a fuel nozzle therein having a well opening freely into said tube and having a second opening into the tube above the top of the well, there being a restrictive passage from the interior of the nozzle to said well. 120 125

8. In a hydrocarbon motor, the combination with the intake pipe and throttle valve, of a carburetor comprising a mixing chamber delivering to said intake pipe and a nozzle in which all the parts are relatively fixed 130

and valveless in operation, said nozzle having a delivery opening slightly above the normal fuel level and comprising an open-ended well with a restrictive passage from

the interior of the nozzle, said nozzle having a second delivery opening well above the first opening and comprising an elongated tube with a restricted passage therethru.

9. In a hydrocarbon motor, the combination with the intake pipe and throttle valve, of a carburetor comprising a mixing chamber delivering to said intake pipe, a Venturi tube below the mixing chamber, and a nozzle in the Venturi tube, all the parts of said nozzle and tube being relatively fixed and valveless in operation, and said nozzle comprising, first, a well open at its top at the contracted part of said tube and having a restrictive passage from the interior of the

nozzle, and second, an elongated extension 20 with a restricted passage therethru and delivering well above the restricted part of the Venturi tube.

10. In a hydrocarbon motor, the combination with the intake pipe and throttle valve, 25 of a carburetor comprising a mixing chamber delivering to said intake pipe, a Venturi tube below the mixing chamber, and a nozzle in the Venturi tube, all the parts of said nozzle and tube being relatively fixed and 30 valveless in operation, and said nozzle comprising, first, a well open at its top and adapted to deliver fuel at low suction, and second, a relatively high outlet adapted to deliver fuel at high suction only. 35

In testimony whereof I affix my signature.

LIONEL M. WOOLSON.
